(57) CLAIM

The ornamental design for a beverage opening device as shown and described.

DESCRIPTION

FIG. 1 is a perspective view of a beverage opening device, in accordance with our new design;

FIG. 2 is a left side view thereof;

FIG. 3 is a right side view thereof;

FIG. 4 is a front elevational view thereof;

FIG. 5 is a back elevational view thereof;

FIG. 6 is a top view thereof; and,

FIG. 7 is a bottom view thereof.

The broken lines in the drawings depicts portions of the beverage opening device that form no part of the claimed design.
